UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

ANNUNCIATOR.

SPECIFICATION forming part of Letters Patent No. 735,511, dated August 4, 1903.

Application filed August 3, 1900. Serial No. 25,848. (No model.)

To all whom it may concern:

Be it known that I, EDWARD M. HEWLETT, a citizen of the United States, residing at Schenectady, county of Schenectady, State of New York, have invented certain new and useful Improvements in Annunciators, of which the following is a specification.

This invention relates to electric annunciators, the object being to adapt the annunciator-drop after being actuated to communicate a determinate signal to be set to a new position, affording an indication to an attendant that the signal has been received and yet leave the parts in a position indicating that the annunciator is not in normal position with respect to the circuit.

The device is particularly adapted for service in charging storage batteries. In operating automobiles driven by power derived from storage batteries the latter may be charged by a source of current in the circuit of which is an annunciator of the character described above adapted to release its drop when the batteries are sufficiently charged. The release of the drop closes an alarm-circuit, calling the attention of the attendant to the fact that the battery has been charged. The attendant may then raise the drop to an intermediate position, in which it is supported by a latch. He thereby opens the alarm-circuit, stopping the ringing of the bell or other audible indicator, and opens the charging-circuit. The position of the annunciator-drop serves as a continuing indication of the charging-circuit which was used. The parts may be so adjusted that in this position of the drop its armature will be within the field of force of the controlling-magnet to such an extent that when the full potential of the charging source is again put upon the magnet the armature will be drawn up to a closed position.

My invention comprises various features the novelty of which will be hereinafter more fully described, and definitely indicated in the claims.

In the accompanying drawings, which illustrate the invention, Figure 1 is a side elevation of an annunciator embodying my improvements. Fig. 2 is a front view, parts being broken away. Fig. 3 is a sectional view.

1 represents the insulating support, which may be the switchboard of a charging-station, on the rear of which are bus-bar terminals, such as 2, communicating with terminals 3 3^a on the front of the board, between which is connected the coil 4 of an annunciator-magnet. This is provided with iron heads 5 5^a, forming pole-pieces. The lower head is extended, so as to form a bracket 6 supporting the annunciator parts, a stud 6, secured to the rear end of the bracket, projecting through the switchboard and being firmly clamped thereto by means of a nut, as indicated in Fig. 1. The pole-pieces of the magnet are connected by a piece of non-magnetic sheet metal 7, the ends of which are bent at right angles and secured to the pole-pieces by screws, as indicated in Fig. 1, and the front face of which is provided with an indicating number or character to signify the location or individuality of the annunciator. In ears integral with the bracket 5^a is pivoted an L-shaped armature, of cast-iron, 8, provided with an ear at its top to form a stop 75 for engagement with an adjustment-screw 9. The bracket 5^a is also provided with a depending integral extension having a hook 10, which co-operates with a spring-pressed plunger 11, carried by the armature, which is 80 mounted in a tubular socket secured to the armature and carries a pin having a head or enlargement on the rear end, as indicated at 12 in Fig. 3, the head being larger than the opening in the socket and adapted when 85 pushed in to lie in the path of the hook 10 and may retain the armature in an intermediate position, as indicated in Fig. 3.

When the armature is released, it drops to the dotted position shown in Fig. 1. During 90 charging it is held up by the charging-current, which effects a strong magnetization of the annunciator-magnet. The armature carries a metallic bridge, of copper, 13, which spans two spring-contacts 14 14^a, secured to 95 terminals at the rear of the board and connecting with an alarm-circuit, including a bell or other audible indicator and a battery or other source of electric potential. The annunciator is included in the charging-circuit, 100 and when the battery being charged reaches the required potential the underload-magnet

4 becomes weakened sufficiently to permit the armature 8 to fall under the influence of gravity, thereby closing the alarm-circuit and notifying the attendant that the battery 5 is sufficiently charged. The attendant may then disconnect from circuit the battery being charged, and in order to leave a temporary record of the circuit which did the charging he may hook the annunciator-drop in its 10 intermediate position, as indicated in Fig. 3, thereby leaving the drop-number sufficiently exposed to be seen and stopping the alarm without operating a switch or other part, which would require special attention and by being 15 overlooked might create trouble. On using the same charging-circuit a second time the annunciator-drop may be raised to the position indicated in full lines in Fig. 1, thereby covering its number. If desired, the parts 20 might be so arranged that upon the inclusion of the annunciator-magnet a second time in the charging-circuit the rush of current through the discharged battery of the automobile will draw up the armature of the annunciator from the intermediate position to 25 the closed position—that is to say, the annunciator-magnet will be so adjusted as to pull up the armature from the intermediate position by reason of the very strong magnetic 30 field developed by the first rush of charging-current.

What I claim as new, and desire to secure by Letters Patent of the United States, is—

1. An electric annunciator provided with means for supporting the movable member 35 in intermediate position between the closed and open positions, and a detent forming a part of the drop for engaging said supporting means.

2. An electric annunciator provided with a 40 spring-pressed latch for supporting the drop in a position intermediate between the open and closed positions.

3. An electric annunciator carrying a circuit-closer for an alarm-circuit operated by 45 its drop and provided with means for supporting the drop in a position to permit the indicator of the annunciator to be seen while the alarm-circuit is open.

4. An annunciator comprising an under-load-controlling magnet, and means for supporting the drop in an intermediate position between its full open and closed positions within the grasp of the magnet when it carries 50 full current.

5. An annunciator comprising an under-load-controlling magnet, an alarm-circuit energized by the drop, and means for supporting the drop to hold the alarm-circuit open when the controlling-magnet is deenergized. 55

In witness whereof I have hereunto set my hand this 27th day of July, 1900.

EDWARD M. HEWLETT.
